UNITED STATES PATENT OFFICE.

JOSEPH F. NOECKER, OF BLOOMFIELD, NEBRASKA.

CONVEYER.

Application filed November 8, 1926. Serial No. 147,061.

This invention relates to conveyers, of that type to be used in construction work on roads, in building tunnels and like uses, and has for its object to provide, in a manner as 5 hereinafter set forth, a conveyer of the class referred to with means, positioned at the lower or material receiving end of the belt or elevator, to prevent mud and dirt from getting on the inside thereof and adhering 10 to the roller for the belt and further for cleaning any adhering dirt from the roller during the revolving thereof, whereby the conveyer will not become clogged and its operation retarded.

15 Further objects of the invention are to provide, in a manner as hereinafter set forth, a shielding and scraping means for use in connection with a conveyer of the class referred to and for the purpose aforesaid and 20 which is comparatively simple in its construction and arrangement, strong, durable, compact, thoroughly efficient in its use, readily installed with respect to the lower or material receiving end of the conveyer, 25 and comparatively inexpensive to set up.

With the foregoing and other objects in view the invention consists of the novel construction, combination and arrangement of parts as hereinafter more specifically 30 described, and illustrated in the accompanying drawings, wherein is shown an embodiment of the invention, but it is to be understood that changes, variations and modifications can be resorted to which fall within the 35 scope of the claims hereunto appended.

In the drawings wherein like reference characters denote corresponding parts throughout the several views:

Figure 1 is a fragmentary view, in side 40 elevation, of a conveyer, showing the adaptation therewith of a shielding and a scraping means in accordance with this invention.

Figure 2 is a fragmentary view, in top plan of a conveyer, showing the adaptation therewith of a shielding and scraping means 45 in accordance with this invention.

Figure 3 is a cross sectional view of the conveyer, at the lower or material receiving end thereof, and further illustrating there- 50 with the shielding and scraping means in accordance with this invention.

Figure 4 is a fragmentary view in longitudinal section of the lower or receiving end of a conveyer showing the adaptation therewith of a shielding and scraping means in accordance with this invention.

Figure 5 is a fragmentary view in top plan illustrating the scraper and its support.

Figure 6 is a side elevation of one of the shields or dirt guards.

60

Referring to the drawings in detail 1 and 2 indicate the foot blocks which are placed at the lower or material receiving end of the conveyer. The blocks 1 and 2 are arranged in spaced relation and are formed with laterally extending apertured lugs 3, through which extend holdfast devices 4 for securing the shoe 5, against the upwardly inclined part 6 of the bottom of the said blocks. The shoe 5 projects laterally from each of the blocks. The side bars of the conveyer body are indicated at 7, 8 and the foot blocks 1 and 2 are connected in any suitable manner to the lower ends of the side bars 7 and 8. Each of the foot blocks includes an upstanding lug 9 carrying an adjusting screw 10, see Figure 1. Mounted upon each of the foot blocks is an adjustable supporting plate 11, provided at its rear end with an upstanding apertured lug 12, and with the wall 80 of the aperture threaded to receive the adjusting screw 10. Plate 11 is furthermore provided at its outer side with an apertured lug 13 extending upwardly from the upper face of the plate. The plate furthermore is 85 formed with spaced slots 14 arranged in a row extending longitudinally of the plate, and between a pair of the slots 14 a bearing 15 is arranged. Holdfast devices extend through the slots 14 and also through the 90 foot blocks for connecting the plate 11 to said blocks. The holdfast devices are indicated at 16 and in connection with the slots 14 provide for the lengthwise adjusting of the plates 11 with respect to the foot blocks 95 1 and 2. Mounted in the bearing 15, is the lower roller 17, for the belt or elevator 18. Each plate 11 is provided with depending spaced flanges 19 which overlap the foot blocks 1 and 2, see Figure 3, and the said 100 plates 11, are connected together by a tie rod 20, which extends through the apertured lugs 13 and carries clamping nuts 21 on the ends thereof. Mounted upon the rod 20 and abutting the lugs 13 is a tubular member 22 105 which provides a reinforcement for the rod 20 and also assists in maintaining the lugs 13 in spaced relation. Each of the plates 11 has its upper portion or inner portion, indicated at 23, of greater width than its lower 110 or outer portion 24. The side plates of the conveyer body are indicated at 25, 26 and

110

which are arranged inwardly with respect to the side bars 7 and 8. A dumping or drop pan 27 is positioned against the lower edge of the side bars 7 and 8, at the lower ends 5 thereof, and also positioned against the bottoms of the foot blocks at the upper portion thereof. Coupling members 28 and 29 are arranged between the side plates and the shoe 5 and the side bars 7 and 8. The lower 10 end of the wider part 23 of each plate 11, at the inner side thereof, is provided with an opening 30. The foregoing elements are of known construction, other than the providing of the openings 30 in the plates 11, 15 and are illustrated for the purpose of showing the adaption of a shielding or guarding means and scraping means, in accordance with this invention, arranged in co-operative relation with the lower or material receiving end of the conveyer.

Connected with each plate 11 and with a side plate is a dirt guard, referred to generally by the reference 31. The dirt guards are oppositely disposed with respect to each 25 other and are attached to the outer sides of the plates 11 and side plates 25, 26. The dirt guards are bodily shifted with the plates 11 and the plates 11 are shifted for the purpose of taking up the slack in the 30 belt or elevator 18. The belt or elevator 18 is of the endless type. The dirt guards are of the same construction, but one will be described, as the description of one will apply to the other. The dirt guards act as 35 shields for the lower or receiving end of the conveyer and prevent mud and dirt from getting on the inside of the belt and adhering or sticking to the roller 17.

Each dirt guard comprises a vertically disposed upper portion 32, a vertically disposed lower portion 33 and an inwardly extending and upwardly inclined intermediate portion 34. The upper portion 32 at a 40 point between its vertical center and rear end is formed with a lengthwise extending slot 35. The lower end portion 33 at a point between its vertical center and its rear or lower end is formed with an opening 36. The guard 31 at a point between its vertical 45 center and its upper or forward end is formed with an inverted U-shaped cut-out part 37 which extends from the lower edge of the guard and partly through the intermediate portion 34 and said cut-out part forms 50 a clearance for a bearing 15. The upper end portion 32 of the guard is secured to a side plate by the holdfast device 38 and which extends through the slot 35. The holdfast device 38 and slot 35 provides means where- 55 by the guard can be adjusted lengthwise of that side plate to which the guard is connected. The opening 36 is provided for the passage of the tie rod 20, and a clamp- 60 ing nut on an end of the tie rod 20, clamps 65 the lower end portion 33 against the lug

13, see Figure 3. The guard 31 is of appropriate length and provides a shield which is interposed between the lower end of the side plate and a plate 11. The side plate projects beyond the lower end of a side 70 bar and the guard is positioned at the lower end of the side bar, see Figure 4.

The means for scraping or cleaning the roller 17 is supported from the pair of plates 11 and is positioned forwardly with 75 respect to the roller 17. The said means consists of a carrier 39 formed at each end with a transverse slot 40. Extending through the slots 40 and the openings 30 are holdfast devices 41 which secure the carrier 80 39 to the plates 11. The slots 40, in connection with the holdfast devices 41, provide means whereby the carrier can be adjusted towards and from the roller 17, for the purpose of arranging the scraper or 85 blades 42 in the desired position with respect to the roller 17, to remove the adhering dirt or foreign substances therefrom. The scraper 42 is of less length than the length of the carrier 38 and is secured to the 90 latter by hold fast devices 43. The carrier 39 and scraper 42 are formed with registering openings for the passage of the holdfast devices 43. The holdfast devices 43 detachably connect the scraper 42 to the carrier 39. The dirt removed from the roller 17 is shifted on the belt, and is discharged off the sides thereof into the pan 27 and onto the shoe 5, and when the pan is dropped is discharged from the lower end of the conveyer. The carrier 39 is bodily shifted with the plates 11 when these latter are adjusted. The carrier 39 is independently adjustable 100 with respect to the plates 11. The carrier 39 is bodily shifted with the plates 11 when 105 the dirt guards are bodily carried by the plates 11 during the adjustment of these latter.

It is thought that the many advantages of a means for guarding or protecting or 110 shielding the conveyor belt of a conveyer machine of the type referred to and also for scraping the lower roller for said belt, as hereinbefore set forth can be readily understood, and although the preferred embodiment of the invention is as illustrated and described, yet it is to be understood that changes in the details of construction can be had which will fall within the scope of the invention as claimed.

What I claim is:

1. A means for shielding the lower end of an endless conveyer belt from mud and dirt in a conveyer of the type including a pair of side plates and lower roller bearing plates 125 arranged below the lower ends of the side plates, comprising a pair of oppositely disposed guards, each of said guards consisting of a lower end portion for connecting to a bearing plate, an upper end portion for 130

connection to a side plate and inset with respect to said lower end portion and an inwardly extending and inwardly inclined intermediate portion integral with said end portion.

2. In a conveyer, in combination, a pair of side plates, a pair of adjustable lower belt roller supporting plates positioned below and outwardly with respect to said side plates, oppositely disposed guards connected to said side and supporting plates, a lower belt roller scraping means connected to said supporting plates and bodily shifted therewith on the adjusting of said supporting plates, and means whereby the guards are carried with the supporting plates on the adjusting of the latter.

3. In a conveyer, in combination, a pair of side plates, a pair of adjustable lower belt roller supporting plates positioned below and outwardly with respect to said side plates, oppositely disposed guards connected to said side and supporting plates, a lower belt roller scraping means connected to said supporting plates and bodily shifted therewith on the adjusting of said supporting plates, means whereby the guards are carried with the supporting plates on the adjusting of the latter, and means to provide for the adjusting of said scraping means independent of the adjusting of said supporting plates.

4. Means for protecting the lower side portion of an endless conveyer belt to prevent the entrance of dirt and mud into the belt consisting of a guard extended over said side portion and formed with an upper and a lower end portion and an intermediate portion, said upper end portion inset with respect to said lower end portion and said intermediate portion extending inwardly and at an upward inclination and integral with said end portions. 35

5. Means for protecting the lower side portion of an endless conveyer belt to prevent the entrance of dirt and mud into the belt consisting of a guard extended over said side portion and formed with an upper and a lower end portion and an intermediate portion, said upper end portion inset with respect to said lower end portion and said intermediate portion extending inwardly and at an upward inclination and integral with said end portions. 40

50 In testimony whereof, I affix my signature hereto.

JOSEPH F. NOECKER.
